DEVICE FOR STRAIGHTENING OIL WELLS

Daniel B. Monroe, Denver, Colo.

Application August 22, 1938, Serial No. 226,098

11 Claims.

(Cl. 255—1)

This invention relates to a device for straightening crooked or inclined drill holes when drilling wells with a rotary drilling rig and has for its principal object the provision of a simple, highly-efficient device to be placed between the drill stem and the drill of a rotary rig which will act to automatically direct the bit vertically downward from an inclined hole.

Another object of the invention is to so construct the device that after the hole has been brought to the vertical position, drilling may be continued without removing the straightening device so that less of time in withdrawing the string is eliminated.

15 A still further object of the invention is to provide a device of this character in which the degree of offset may be accurately controlled from the surface by varying the weight placed upon the drill.

20 Other objects and advantages reside in the detail construction of the invention, which is designed for simplicity, economy, and efficiency. These will become more apparent from the following description.

25 In the following detailed description of the invention reference is had to the accompanying drawings which form a part hereof. Like numerals refer to like parts in all views of the drawings and throughout the description.

30 In the drawings:

Fig. 1 is a side elevation of the improved well straightening device partially in section.

Figs. 2, 3, 4, and 5 are horizontal cross sections therethrough, taken on the lines 2—2, 3—3, 35 4—4, 5—5, respectively, Fig. 1.

Fig. 6 is a vertical section through the device illustrating it in place in a drill hole. In this section, the device is illustrated in the vertical drilling position.

40 Fig. 7 is a similar section illustrating the device being used to direct an inclined drill hole back to the vertical position.

In the drawings the drill stem of the drilling rig is indicated at 10 and the drill bit at 11.

45 The improved straightener employs a spring socket joint 12 which is threaded into the lower extremity of the drill stem 10. A hollow drill shaft 13 extends from the socket joint to the drill 11. There is a square portion 14 adjacent the upper extremity of the drill shaft 13. This square portion passes through a square hole in a bushing 15 which is threaded into the bottom of the socket joint 12. The square portion 14 terminates in a spherical faced head 16 which 50 prevents withdrawal of the shaft from the spring

housing. A spring cup 17, having a spherical concavity engaging the spherical head 16, is constantly forced downwardly against the head by means of a relatively heavy compression spring 18.

5 When the shaft 13 is at its lowermost position, and the spring 18 is fully extended, the head 16 fits snugly in the bottom of the socket joint 12 and rests against a conical seat on the bushing 15 which holds it rigidly in alignment 10 with the drill stem 10. As the weight on the drill stem is increased, the spring 18 will be compressed allowing the socket joint to slip downwardly on the drill shaft 13 until the head 16 enters an enlarged chamber 19 in the socket 15 joint. This frees the head so that it may move to the side, as shown in Fig. 7, to allow the shaft 13 to swing out of alignment with the drill stem 10. The square hole through the bushing 15 is tapered, as indicated at 20, to permit angular 20 movement between the drill stem 10 and the shaft 13. As soon as the weight on the drill stem is released, the spring 18 will again force the head to its seat in the bushing 15 and bring the shaft 13 into alignment as shown in Fig. 6. 25

An eccentric, counterweight 21 is rotatably mounted about the shaft 13 so that it may swing to the lower side thereof should the shaft be inclined. This counterweight carries flanged sleeves 22 and 23 at its upper and lower extremities respectively. These sleeves are telescopically fitted into the counterweight but are keyed against rotation therein.

Between each flange and the counterweight, and at each extremity thereof, is a compressible 35 rubber buffer 24. These buffers are secured to the counterweight and to the flanges 22 and 23 and are faced in opposite directions. The lower sleeve flange rides against a thrust bearing 25 on the drill 11 and the upper sleeve flange supports a flanged thrust member 26 on similar thrust bearings 27. The thrust member 26 is free to move vertically on the square portion 14 of the shaft and contacts the bushing 15.

Let us assume that it has been ascertained that 45 a drill hole, such as illustrated in Fig. 7, is being drilled on an incline from the vertical. The above straightener is attached to the lower extremity of the drill stem and lowered into the well. When the bottom is reached, the incline of 50 the well will cause the counter weight 21 to swing toward the lower side thereof. This places the upper buffer 24 toward the lower side of the hole and the lower buffer 25 opposite the higher side. Weight is now brought to bear upon the drill 55

stem to compress the spring 18 and release the head 16. This causes the bushing 15 to force the thrust member 26 to compress the two buffers and project them outwardly, as shown in Fig. 7. This 5 causes lower buffer to force the drill toward the low side and the upper buffer to force the upper extremity of the shaft 13 toward the high side of the drill hole. Drilling is now resumed with the drill shaft 13 maintaining its new angular 10 position, thus gradually turning the hole back toward the vertical position.

When the vertical position is reached, the weight on the drill stem is lessened allowing the position of Fig. 6 to be resumed so that normal 15 straight drilling may be continued without withdrawing the straightener.

If desired, a shear pin 28 may be inserted through the joint 12 into the head 16 to hold the mechanism in the straight extended position 20 until sufficient weight is brought to bear to shear the pin 28.

The square portion 14 on the shaft 13 cooperates with the square hole in the bushing 15 to transmit the rotative power to the drill 11 at all 25 angular positions thereof.

The shaft 13 is formed with a water core 29 and the cup 17 is formed with a water passage 30 so that the water from the drill stem may flow 30 downwardly through the spring housing and shaft to the drill.

While the invention has been described as particularly valuable for straightening inclined holes to bring them to the vertical position, it is also useful for deflecting a straight hole to drill 35 around an obstruction such as lost tools, etc. In the latter case, weight placed upon the device will compress the spring 18 to create a loose joint which will allow the shaft 14 to swing in the spring socket to an angle.

40 The amount of angle and the direction thereof may be pre-set in advance, if desired, by placing a locking screw at the point "A", Fig. 7, before the device is lowered in the hole. This screw will shear when drilling is commenced.

45 While a specific form of the improvement has been described and illustrated herein, it is desired to be understood that the same may be varied, within the scope of the appended claims, without departing from the spirit of the invention.

50 Having thus described the invention, what is claimed and desired secured by Letters Patent is:

1. A device for straightening well drill holes comprising: a socket member for attachment to the lower extremity of a drill stem; a drill shaft 55 swingingly depending from said socket member; means for attaching a drill bit to the lower extremity of said drill shaft; and means for locking said shaft in alignment with said stem when desired.

2. A device for straightening well drill holes comprising: a socket member for attachment to the lower extremity of a drill stem; a drill shaft 65 swingingly depending from said socket member; means for attaching a drill bit to the lower extremity of said drill shaft; and means operable from the surface for locking said shaft in alignment with said stem when desired.

3. A device for straightening well drill holes 70 comprising: a socket member for attachment to the lower extremity of a drill stem; a drill shaft having its upper extremity in said socket member; a head on said drill shaft for preventing its withdrawal from said socket member, said 75 socket member being chambered to allow said

head to swing out of alignment with said stem; a seat for said head formed about said shaft, said seat being in axial alignment with said stem; and spring means for urging said head against said seat to bring said shaft into alignment with 5 said stem; and a drilling bit carried on the lower extremity of said shaft.

4. A device for straightening well drill holes comprising: a socket member for attachment to the lower extremity of a drill stem; a drill shaft 10 having its upper extremity in said socket member; a head on said drill shaft for preventing its withdrawal from said socket member, said socket member being chambered to allow said head to swing out of alignment with said stem, the upper portion of said shaft being noncircular; a bushing, having a passage for the non-circular portion of said shaft, threaded into said socket member to hold said head in place therein; a seat on said bushing for the reception of said head, said seat being positioned concentric of said stem; a compression spring in said socket member urging said head from said chamber and against said seat; and a drilling bit on the lower extremity of 20 said shaft.

25 5. A device for straightening well drill holes comprising: a socket member for attachment to the lower extremity of a drill stem; a drill shaft having its upper extremity in said socket member; a head on said drill shaft for preventing its 30 withdrawal from said socket member, said socket member being chambered to allow said head to swing out of alignment with said stem; the upper portion of said shaft being non-circular; a bushing, having a passage for the non-circular portion of said shaft, threaded into said socket member to hold said head in place therein; a seat on said bushing for the reception of said head, said seat being positioned concentric of said stem; means for holding said head in said seat 40 until a predetermined weight is placed on said drill stem; and means for mounting a drilling bit on said shaft.

35 6. A device for bringing inclined well drill holes to perpendicular including a drill shaft; and vertically compressible means on opposite sides of and at different elevations on said shaft arranged, when compressed, to project outward from said shaft against the wall of the well to force the lower extremity of said shaft in one 50 direction and the upper extremity in the opposite direction.

7. A device for bringing inclined well drill holes to perpendicular including a drill shaft; vertically compressible means on said shaft arranged, when compressed, to project outward from said shaft against the wall of the well to deviate said shaft from its course; and a counter-weight mounted on said shaft to control the direction of projection of said compressible 60 means.

55 8. A device for straightening inclined well drill holes comprising: a rotary drilling stem; a socket member on the lower extremity of said stem; a drill shaft depending from said socket member, 65 said socket being vertically movable on the upper extremity of said shaft; means for preventing relative rotary movement between said shaft and said socket member; means carried by said drill shaft and actuated by the downward movement 70 of the socket member thereon so as to project from opposite sides of said shaft into contact with the wall of the drill hole at different elevations to deviate said shaft from its course; means acting to constantly urge said shaft into align- 75

ment with said stem and means for attaching a drilling bit at the lower extremity of said shaft.

9. A device for straightening inclined well drill holes comprising: a rotary drilling stem; a 5 socket member on the lower extremity of said stem; a drill shaft depending from said socket member, said socket being vertically movable on the upper extremity of said shaft; means for preventing relative rotary movement between 10 said shaft and said socket member; an eccentric counterweight free to rotate about said shaft; resilient, vertically compressible means carried by said counterweight at one side of said shaft; and means actuated by the downward movement of said socket member on said drill shaft 15 for compressing said compressible means to cause the latter to be projected outward against the wall of said drill hole to exert a deviating effect on said shaft.
10. A device for straightening inclined well 20 drill holes comprising: a rotary drilling stem; a socket member on the lower extremity of said stem; a drill shaft depending from said socket member, said socket being vertically movable on the upper extremity of said shaft; means for preventing relative rotary movement between 25 said shaft and said socket member; an eccentric counterweight free to rotate about said shaft; a

flanged sleeve telescopically projecting from each extremity of said counterweight a compressible rubber buffer positioned between each sleeve and said counterweight, the upper buffer projecting on the side toward said weight and the lower 5 buffer projecting on the side from said weight; and compressing means in the path of movement of said socket member on said shaft for compressing said buffers so that they will project outwardly against the wall of said drill hole. 10

11. An oil well drill bit guide comprising: a downwardly depending, chambered socket member; a drill shaft depending from said socket member; a bushing closing the chamber of the socket member about said drill shaft and preventing withdrawal of the latter, said bushing having a passage for said shaft, said passage being enlarged at its extremity to allow said shaft to swing in any direction, said bushing being free to move longitudinally on said shaft so that the chamber in the socket member may be brought opposite the head of said shaft; means for preventing relative rotation between said bushing and said shaft; means for connecting said socket member to a drill stem; and means 20 for connecting said shaft to a drill bit. 25
